US00D721947S

(12) **United States Design Patent**
Wendt

(10) **Patent No.:** **US D721,947 S**
(45) **Date of Patent:** **** Feb. 3, 2015**

(54) **CONNECTING ELEMENT**

(71) Applicant: **PilePro LLC**, Austin, TX (US)

(72) Inventor: **Roberto Redondo Wendt**, Austin, TX (US)

(73) Assignee: **PilePro LLC**, Austin, TX (US)

(**) Term: **14 Years**

(21) Appl. No.: **29/470,500**

(22) Filed: **Oct. 22, 2013**

(30) **Foreign Application Priority Data**

Apr. 22, 2013 (DE) 40 2013 001 869

(51) LOC (10) Cl. **08-08**

(52) U.S. Cl.

USPC **D8/382**

(58) **Field of Classification Search**

USPC D8/382, 394-395; D25/121, 119, 61; 405/274, 277, 278-279; 24/370, 346, 24/573.09

See application file for complete search history.
